UNITED STATES PATENT OFFICE.

CASSIUS HOLTON, OF READING, PENNSYLVANIA.

SASH-CORD PULLEY.

SPECIFICATION forming part of Letters Patent No. 259,155, dated June 6, 1882.

Application filed March 28, 1882. (Model.)

To all whom it may concern:

Be it known that I, CASSIUS HOLTON, of Reading, in the county of Berks, and in the State of Pennsylvania, have invented certain new and useful Improvements in Window-Pulleys; and I do hereby declare that the following is a full, clear, and exact description thereof, reference being had to the accompanying drawings, and to the letters of reference marked ⁵ thereon, making a part of this specification.

This invention relates to certain improvements in window-frame pulleys; and it has for its objects to provide certain means whereby such pulleys may be secured in the window-frames without the use of screws or other similar fastening devices, as more fully hereinafter specified. These objects I attain by the means illustrated in the accompanying drawings, in which—

²⁰ Figure 1 represents a transverse sectional view of a window-frame, showing my improved device applied thereto; Fig. 2, a perspective view of my improved device detached; Fig. 3, a similar view of a modification of my device; ²⁵ and Fig. 4 represents a vertical section of the forward part of the sheave-casing.

The letter A indicates the shell of my improved device, which is constructed of cast metal or other suitable material, and with a ³⁰ shank, B, which is adapted to extend across the space between the walls of the frame and into a suitable aperture in the rear wall of the said frame, so as to hold the shell without the use of screws or other similar fastening devices.

³⁵ The shell and its shank are provided on opposite sides with longitudinal ribs C, which set into the sides of the mortise D and opening D' in the frame and weight-box of the window, which form the seat for the shell, so as to hold ⁴⁰ the shell in place without the use of screws or other similar fastening devices. The outer

edge of the shell is provided with a flange, E, which sets against the edge of the mortise D in the window-frame or weight-box, and serves to assist in holding the shell in place.

As indicated in the modification illustrated in Fig. 3 of the drawings, the shell is constructed in two parts, with interlocking lugs, G, which serve as a means to adjust the parts together. The edges of the shell or casing and its shank, when thus constructed, are formed with serrations or corrugations H, which serve the same purpose as the ribs before mentioned. The letter L indicates the sheave of the pulley, which is journaled between the walls of the ⁵⁰ shell in the usual manner.

The shank of the shell may be of any suitable shape in cross-section; but it is preferably of such form as to fit readily in an aperture made by an auger or other boring-tool for ⁵⁵ cheapness and convenience.

Having thus described my invention, what I claim and desire to secure by Letters Patent, is—

⁶⁰ 1. In a window-pulley, the shell provided with a shank at its rear, adapted to set in an aperture in the rear wall of the window-frame and weight-box to hold the shell in place, substantially as specified.

⁶⁵ 2. In a window-frame pulley, the shell provided with a shank adapted to set in an aperture in the window-frame and weight-box, and with longitudinal projections, substantially as and for the purpose specified.

⁷⁰ In testimony whereof I affix my signature, in presence of two witnesses, this 16th day of March, 1882.

CASSIUS HOLTON.
